UNITED STATES PATENT OFFICE.

JOSEPH J. REILLY, OF NEWARK, NEW JERSEY.

WASHTUB.

1,039,803.

Specification of Letters Patent.

Patented Oct. 1, 1912.

Application filed June 29, 1911. Serial No. 635,927.

To all whom it may concern:

Be it known that I, JOSEPH J. REILLY, a citizen of the United States, and a resident of Newark, in the county of Essex and State 5 of New Jersey, have invented a new and Improved Washtub, of which the following is a full, clear, and exact description.

My invention relates to combination tubs and wringers, my more particular purpose 10 being to provide a tub having a special form whereby it is adapted to be used in connection with a wringer so located within it that the combination of the tub and wringer presents a number of advantages 15 in the conjoint use of these parts.

More particularly stated, my invention comprehends a tub provided with partitions whereby the space within it is sub-divided into compartments, and a wringer disposed 20 within the tub and mounted upon the partitions in such manner that in use the water expressed from the stock by the action of the wringer first flows freely into one of the compartments and is thence drained 25 out without interfering with the water or stock contained in other compartments.

My invention further comprehends various details of construction whereby the wringer, the tubs, and the combination of 30 the wringer and tubs are improved in efficiency.

Reference is to be had to the accompanying drawings forming a part of this specification in which like characters of reference 35 indicate corresponding parts in all the views, and in which—

Figure 1 is a substantially vertical section on the line 1—1 of Fig. 2, looking in the direction of the arrow; and Fig. 2 is a 40 cross section substantially on the line 2—2 of Fig. 1, looking in the direction of the arrow.

A tub is shown at 3, and has generally a box-like form. This tub rests upon legs 4 and brackets 5, and is provided with two partitions 6, 7, located vertically within it and disposed parallel to each other. A drain pipe 8 is provided with three branches 9, 10, 11, these branches being connected 45 with different portions of the tub. The partition 6 is provided with a gap 12, the partition 7 being similarly provided with a gap 13, these two gaps being in registry with each other. The tub 3 is provided 50 with a gap 14 located within its outer or front wall, and between the partitions 6, 7.

The wringer is shown more particularly in Fig. 2 and comprises a frame 15 which is held in position by aid of a screw bolt 16, the latter extending through a hole 16^a 60 in the partition 7. The wringer is provided with a revoluble shaft 17, and mounted upon the outer end of the latter is a crank arm 18 by aid whereof the shaft is turned. The wringer is further provided 65 with rollers 19, a slide 20, and a leaf spring 21, these parts being of the usual or any desired construction. The tub is provided with a swinging lid 22 whereby it may be closed. Water pipes 23 are connected with 70 the upper portion of the tub, and associated with these water pipes are hand valves 24.

In order to support the wringer it is lowered between the partitions 6, 7 until 75 one corner of the frame 15 engages the adjacent inclined wall of the tub, and the screw bolt 16 is next inserted and forced against the frame 15 of the wringer so as to hold the latter firmly in position. The 80 mere manner of attaching the wringer forms no part of my invention.

The partitions 6, 7 are so arranged that the bottoms of the gaps 12, 13 serve as overflow barriers, that is to say, if the water be 85 left running freely into the tub, it can climb no higher than the common level represented by the bottoms of the gaps 12, 13. The water flows through either or both of these gaps and makes its escape through the 90 drain pipe 9. The space 25 between the two partitions 6, 7 thus constitutes a drainage compartment. It is adapted to receive water running downwardly from the wringer, this water, however, immediately making its 95 escape. Two spaces 26, 27 disposed on opposite sides of the partitions 6, 7 constitute the compartments for holding water, together, with the stock of clothing upon which the wringer is to operate. Water 100 may, by aid of the pipes 9, 11, be let out of the compartments 6, 7 in the usual manner.

The operation of my device is as follows: One of the compartments 26, 27 contains the stock of clothing to be subjected to the action of the wringer and is filled with water by aid of the adjacent hand valves 24. Any excess of water which flows into this compartment is leveled off by virtue of the fact that the water cannot climb higher than the 110 bottom of the gap 13. A piece of clothing is now gathered up by hand and inserted in

the wringer. The hand crank 18 being turned, the piece of clothing is, by the action of the rollers 19, passed from one compartment 26, 27 to the other and is there comparatively dried in the compartment toward which it travels. The water squeezed out by the action of the wringer within the compartment 25 drops down and finds its way out through the pipes 10, 8, as above described.

10 The clothing can be passed in either direction through the wringer, and if desired, both the compartments 26, 27 may contain water.

15 I do not limit myself to any particular materials to be used in any of the parts above described. Neither do I limit myself in all instances to the precise arrangement shown, the scope of my invention being commensurate with my claims.

20 The crank 18 is removable and may, therefore, be taken off at the will of the operator. The lid 22 may be closed without disturbing the position of the wringer.

25 Having thus described my invention, what I claim as new and desire to secure by Letters Patent is:—

1. The combination of a tub, a pair of

partitions mounted therein and suitably spaced apart, each partition being provided with a gap, the space between the partitions being adapted to receive a wringer, the bottoms of the said gaps being disposed below the upper edge of the said tub whereby material may pass through the wringer from one side of the tub to the other, together with a drain pipe communicating with the said space and the said sides of the tub.

2. The combination of a tub, a pair of partitions within the tub, the partitions being suitably spaced apart, the space between the partitions being adapted to receive a wringer, the said space being provided with a drain pipe whereby, when the wringer is operated, the water dripping therefrom may be collected in the space between the partitions, the drain pipe carrying off the said water.

30 In testimony whereof I have signed my name to this specification in the presence of two subscribing witnesses.

JOSEPH J. REILLY.
